(57) **CLAIM**

The ornamental design for a fishing lure, as shown and described.

DESCRIPTION

FIG. 1 is a front and side perspective view of a fishing lure showing my new design;

FIG. 2 is a top plan view thereof;

FIG. 3 is a bottom plan view thereof;

FIG. 4 is a left side elevation view, the right side elevation view is a mirror image thereto;

FIG. 5 is front view thereof;

FIG. 6 is an rear view thereof;

FIG. 7 is an alternate perspective view thereof showing a different body portion;

FIG. 8 is an alternate perspective view thereof showing a different body portion and propellor; and,

FIG. 9 is an alternate perspective view showing a different body portion and propellor.

The broken lines showing the body of the lure, the hooks, hook attachment, the streamers, the eyelet, and propellor are for illustrative purposes only and forms no part of the claimed design.
